UNITED STATES PATENT OFFICE.

EDWARD S. PEAKE, OF WESTERVILLE, OHIO, ASSIGNOR TO THE KILGORE MFG. COMPANY, OF WESTERVILLE, OHIO, A CORPORATION OF OHIO.

TOY PISTOL.

Application filed December 24, 1926. Serial No. 156,819.

The present invention relates to toy pistols of the type including mechanism adapted to feed automatically a strip of caps across an anvil, and to explode them successively, all through operation of a trigger having associated therewith strip feed mechanism, and means for actuating the cap exploding hammer.

Pistols of this type ordinarily include 10 spring means for tensioning the cap feed pawl and hammer retracting or actuating pawl, as illustrated, for instance, in the patent to Rohn, 1,144,791, June 29, 1915.

An object of the invention is to improve 15 pistols of the type disclosed in said patent by rendering the cap feed means and the means for retracting the hammer more positive in operation and more durable.

It has been found that when reliance is 20 had upon a torsion spring, such as is illustrated in the patent, action of the feed and hammer pawls becomes sluggish after some use. This is probably due to the effect of the explosions upon the torsion spring materially shortening the life of the spring. 25 Moreover, it has been found that a spring of this type, due to the fact that the tension is placed upon limited lengths of the same, is comparatively short in a toy pistol as 30 compared to the life of a coil spring, and more specifically, one of the longitudinally extensible type.

The variation in the action of the spring mechanism in other parts of a toy pistol 35 is not so noticeable, but in the operation of the feed pawl and hammer pawl, it is essential that the spring be always fairly resilient and quick acting, since these parts must be nicely timed in their operation.

Briefly, therefore, the present invention 40 seeks to improve the operation of the cap feed and trigger actuating pawls by rendering the same more positive and accurate in operation, and seeks to provide an arrangement of parts which will materially lengthen 45 the life of this mechanism and retain the desired accuracy and positive character of its operation.

A further object of the invention is to

provide a mechanism which may be more 50 conveniently assembled and repaired.

Referring to the accompanying drawings, 55 wherein there is shown a preferred embodiment of the invention:

Figure 1 is a side elevational view of the 60 operating mechanism with one side of the pistol casing removed.

Figure 2 is a view similar to Figure 1, 65 showing the position of the parts substantially at the end of a trigger operation.

Figure 3 is a fragmentary view showing 70 the mounting of the cap feed and hammer pawls on the trigger.

Referring to the drawings for a more 75 detailed description, the invention is shown as applied to a pistol having a casing of conventional design including a handle H, barrel B and trigger guard T.

The casing is formed interiorly to provide 80 a cap strip feed plate 10, in the form of a vertically extending wall, which, at its upper end, provides an anvil 11, over which the cap strip 12 is fed from a roll of caps 13, positioned upon a roll-carrying pin 14.

A hammer 15 is pivotally mounted at 85 16, substantially above and to the rear of a trigger 17, having a pivot 18. The trigger carries a cap feed pawl 19, having a laterally directed flange 20 adapted to engage a strip of caps and feed it over the plate 10 as the trigger 90 is retracted. The feed pawl 19 is mounted for bodily movement with the trigger, and for this purpose, is carried upon a stud 21, formed upon a trigger extension 22. The sear or hammer retracting pawl 23 has a 95 shoulder 24 adapted to engage a lug 25 upon the hammer, and is mounted upon the trigger by means of the stud 21. In other words, the feed and hammer pawls are coaxially mounted for independent pivotal movement, and also for bodily movement with the trigger.

To maintain the feed pawl against the plate 10 as the trigger is retracted, a longitudinally extensible coil spring 26 is anchored at 27 to the hammer, or, in other words, to a part of the pistol which is relatively fixed with respect to the axis or stud

21, upon which the feed pawl is mounted. Thus the feed pawl, as it is forced against the plate 10 by upward movement of the trigger extension 22, moves pivotally about 5 the stud 21 away from the point of anchorage 27 of the spring 26 which, it will be observed, is secured at its other end to the feed pawl. This action serves to extend and tension the spring 26. By this arrangement, 10 the feed pawl is accurately and positively tensioned and is independent of the position of the trigger pawl which has an independent pivotal movement about the stud or axis 21.

15 The use of an extensible coil spring is particularly important, since the tension of a spring of this type is distributed substantially throughout the spring and is not restricted, as in the case of torsion springs, 20 which have heretofore been used, to a limited portion of the spring. Furthermore, a spring of this character may be readily applied, and should replacement of the same become necessary for any reason, a new 25 spring need simply be secured at its ends to the feed pawl and trigger.

The hammer pawl 23 has secured to a lug 28 thereon, one end of a longitudinally extensible coil spring 29, which at its other end 30 is looped about a pin 30 within the handle of the pistol, the pin constituting a fixed portion of the pistol relative to which the feed pawl moves pivotally about its axis 21, and also bodily, as the trigger is retracted. 35 It will be observed that the action of this spring is very direct, and as the trigger is actuated, the spring is stretched along a line substantially coincident with its axis. Thus there is substantially no distortion of the 40 spring or torsional action, which is also true with respect to the feed pawl spring 26.

It has been found in actual use of pistols of this type that the operation of this 45 spring mechanism is a decided improvement upon the action of torsion springs and the like, which have been ordinarily employed in this type of pistol for tensioning the cap feed and hammer pawls.

50 It will be understood, of course, that the invention is not restricted to the details of construction illustrated and described, and that such modifications are within the scope of the invention as come within the meaning of the following claims.

55 I claim:

1. In a toy pistol, an anvil, a cap strip feed plate, a hammer mounted for movement toward and from the anvil, a pivotally mounted trigger, a cap strip feed pawl carried by said trigger and mounted for independent pivotal movement together with bodily movement with the trigger, a hammer actuating pawl carried by said trigger and pivotally movable independently of the trigger and independent longitudinally ex-

tensible coil springs for said pawls, one anchored at one end to a part of the pistol fixed relatively to the feed pawl axis and secured at its other end to the feed pawl, and the other anchored at one end to a fixed part of the pistol and secured at its other end to the hammer pawl.

2. In a toy pistol, an anvil, a cap strip feed plate, a hammer mounted for movement toward and from the anvil, a pivotally mounted trigger, a cap strip feed pawl carried by said trigger and mounted for independent pivotal movement together with bodily movement with the trigger, a hammer actuating pawl carried by said trigger and pivotally movable independently of the hammer and independent longitudinally extensible coil springs for said pawls, one anchored at one end to the trigger and secured at its other end to the feed pawl, and the other anchored at one end to a fixed part of the pistol and secured at its other end to the hammer pawl.

3. In a toy pistol, an anvil, a cap strip feed plate, a hammer mounted for movement toward and from the anvil, a pivotally mounted trigger, a cap strip feed pawl mounted directly upon the trigger for bodily movement therewith and having a pivotal movement independently of said trigger about an axis on said trigger, a hammer actuating pawl mounted directly on the trigger for bodily movement therewith, and pivotally movable about an axis on the trigger, and independent longitudinally extensible coil springs for said pawls, one anchored at one end to the trigger and secured at its other end to the feed pawl, and the other anchored at one end to the fixed part of the pistol and secured at its other end to the hammer pawl.

4. In a toy pistol, an anvil, a cap strip feed plate, a hammer mounted for movement toward and from the anvil, a pivotally mounted trigger, a cap strip feed pawl mounted directly upon the trigger for bodily movement therewith and having a pivotal movement independently of said trigger about an axis on said trigger, a hammer actuating pawl mounted directly on the trigger for bodily movement therewith, and pivotally movable about an axis on the trigger, and independent longitudinally extensible coil springs for said pawls, one anchored at one end to a part of the pistol relative to which the feed pawl moves pivotally during its feeding movement and secured at its other end to the feed pawl, and the other anchored at one end to the fixed part of the pistol and secured at its other end to the hammer pawl.

5. In a toy pistol, an anvil, a cap strip feed plate, a hammer mounted for movement toward and from the anvil, a pivotally mounted trigger, a cap strip feed pawl mounted

directly upon the trigger for bodily movement therewith, and having a pivotal movement independently of said trigger about an axis on said trigger, a hammer actuating pawl mounted directly on the trigger for bodily movement therewith and pivotally movable about an axis on the trigger coaxial with the axis of said feed pawl, and independent longitudinally extensible coil springs

for said pawls, one anchored at one end to the trigger and secured at its other end to the feed pawl, and the other anchored at one end to the fixed part of the pistol and secured at its other end to the hammer pawl.

In testimony whereof I have hereunto set 15
my hand.

EDWARD S. PEAKE.
